Primary Examiner — Robin V Webster**CLAIM**

The ornamental design for a container for a handheld dispensing device, substantially as shown and described.

DESCRIPTION

FIG. 1 is an isometric view of the container of the present invention;

FIG. 2 is a front elevation view of the container of FIG. 1; and, FIG. 3 is a top plan view of the container of FIG. 1. The broken lines represent environmental structure and form no part of the claimed design.
